UNITED STATES PATENT OFFICE.

LOGAN L. MALLARD, OF NORFOLK, VIRGINIA.

WALKING TOP.

Application filed January 16, 1928. Serial No. 81,775.

This invention relates to new and useful improvements in tops and the primary object of the invention is to provide a top of any preferred character with an improved 5 peg whereby the top when spun will travel or "walk" over the surface of the ground or floor during the entire spinning operation.

A further object of the invention resides in providing an improved peg to accomplish 10 a "walking" of the top when spun, which peg has its lower face serrated.

A still further object resides in providing a peg having a serrated face, the serrations being cut to extend radially from the center 15 of the engaging face of said peg and the walls of said serrations being cut on predetermined angles, with respect to one another.

A still further object resides in providing 20 a peg of the character referred to which is applicable to all tops which are spun on a flat surface, the peg being of such simple construction as to be readily applied to the peg already in use on the top.

A still further object resides in providing 25 a device which is simple and durable in construction, inexpensive to manufacture and one which will be very efficient and amusing in use.

With these and other objects in view my 30 invention consists in the novel features of construction, combination and arrangement of parts as will be hereinafter referred to and more particularly pointed out in the 35 specification and claims.

In the accompanying drawing forming a part of this application.

Figure 1 is a side elevation of a spring top, 40 with parts broken away and parts in section, and having my improved peg applied thereto,

Figure 2 is a bottom plan view thereof, and

Figure 3 is an enlarged side elevation of 45 the peg removed from the top, parts being broken away.

In describing the invention, I shall refer to the drawing in which similar reference characters designate the corresponding parts throughout the several views and in which 1 50 designates a conventional type of spring top having the central spindle 2 thereon received through the central bore of a holder 3. As stated, this is a conventional type of spring top, shown for purposes of clear illustration and parts have been broken away to disclose

certain well known features for operating a top of this character, but it will be understood that any form of surface spinning top 60 may be utilized in carrying out my invention.

My invention contemplates the provision of an improved peg and to this end I provide a short stem 4 which is secured in any fashion desired to the top body to depend a 65 short distance from the lower face thereof, said stem having a head 5 formed integral with its outer end. This head member may be of any preferred and desired shape, size or thickness but is preferably hexagonal in 70 plan. The outer face of this head member which engages the surface of the ground or floor is grooved radially as shown at 6 to provide a plurality of serrations and the walls of these grooves are cut on different in- 75 clinations, so that the pair of walls of each groove include a long sloping or inclined wall 7 and a short sharply inclined wall 8. In this manner the short and long inclined walls of the grooves will be alternated 80 throughout the surface of said head member

5. The effect of the grooves constructed as shown and described is to provide substantially a series of teeth which, when coming in contact with the surface of the ground or floor when the top is spun, will cause the latter to move or travel at a considerable rate of speed over said surface. Thus the top so constructed may be termed a "walking" or travelling top. It will be seen also from the 90 drawing that the short inclined faces or walls 8 of the grooves 6 are in position to give the greatest travelling or "walking" effect to the top as the latter is spun in the direction of the arrow shown in Figure 1. It has been 95 discovered by experience that the short inclined faces referred to give the greatest effect desired in the spinning of the top and the cutting of the walls of the grooves in this manner has been accomplished accord- 100 ingly.

Whether applied to a string top, spring top, hand top or any other form of top which is spun upon a surface where a peg is desired, my improved form of peg is ex- 105 ceptionally desirable in causing the top to travel as it is spun. It may be here stated that the movement of a top over the surface during the spinning operation is a desirable one, the same being exceptionally pleasing 110 and amusing to the player and the onlookers.

Obviously, the operation of a top con-

2
structed in accordance with my invention will be readily understood from the above description and it will be seen that I have provided a simple, inexpensive and efficient means for carrying out the objects of the invention.

While I have particularly described the elements best adapted to perform the functions set forth, it is obvious that various changes in form, proportion and in the minor details of construction may be resorted to, within the scope of the appended claims, without departing from the spirit or sacrificing any of the principles of the invention.

15 Having thus described my invention, what I claim is:

1. A spinning top comprising a body and a peg therefor provided with a head, the surface-engaging face of said head being serrated and the serrations having the walls thereof inclined alternately with long and short faces, as and for the purposes described. 20

2. A spinning top comprising a body and a peg therefor provided with a head at its outer end, the ground-engaging face of said head being provided with radial grooves, the walls of each groove being inclined to provide respectively long and short bevel faces, as and for the purposes described. 25 30

In testimony whereof I affix my signature.

LOGAN L. MALLARD.
